GAS TANK CAP LOCK

Leonard Rydell, Wausau, Wis.

Application July 6, 1935, Serial No. 30,175

2 Claims.

(Cl. 70—50)

- My invention relates generally to means for locking the cap of the filling neck of an automobile gasoline tank to prevent theft of the gasoline in the tank, and particularly to an electrical lock installed within the filling neck and having normally a position in which it locks the cap on the neck, but which may be electrically operated into another position in which the cap is unlocked with respect to the filling neck.
- An important object of my invention is to provide a simple and mechanically and electrically efficient device of the character described which is electrically operable only while the ignition switch of the automobile is in the "on" position, which position of the ignition switch cannot be achieved without the use of the ignition key.

Other important objects of the invention will be apparent from a reading of the following description in connection with the drawings, wherein for purposes of illustration I have shown a preferred embodiment of my invention.

In the drawings:—

Figure 1 is a general side elevational view of the device of the invention.

Figure 2 is a top plan view of Figure 1 with the cap removed.

Figure 3 is a transverse vertical sectional view taken through Figure 1 approximately on the line 3—3 and looking toward the right in the direction of the arrows.

Figure 4 is a transverse vertical sectional view taken through Figure 1 approximately on the line 4—4 and looking toward the left in the direction of the arrows.

Figure 5 is a bottom plan view of the cap.

Figure 6 is a horizontal sectional view showing the switch on the filling neck.

Referring in detail to the drawings, the numeral 5 generally designates the automobile gasoline tank in the top or side of which is mounted the filling neck 6 on which is the filling neck cap 7.

In accordance with the present invention one side of the filling neck 7 has an interior closed electro-magnet containing chamber 8 in which is mounted a vertical solenoid electro-magnet 9 in which works the lock plunger 10 which has a helical spring 11 engaged with its bottom and located between the plunger and the bottom of the chamber 8 which normally keeps the plunger 10 in an elevated locking position. A magnetically permeable head 12 is located on the plunger 10 in magnetic relation to the electro-magnet, and this head has a cut away portion 13 at one side which cooperates with the shoulder 14 formed in the side of the filling neck, whereby the

head 12 acts as a stop in conjunction with the shoulder 14 for limiting the upward movement of the plunger under the impetus of the spring 11. The upper part of the plunger works through a bracket 15 adjacent the upper end of the filling neck, whereby the plunger is steadied and its action made more efficient. The side of the filling neck 7 is downwardly tapered as indicated by the numeral 16 to join the shoulder 14, and the side of the chamber 18 extends outwardly of the 10 side of the filling neck as clearly shown in Figures 2 and 4.

Alongside the exterior portion of the chamber 8 is a switch casing 17 of generally rectangular form which is removably mounted by a means 18 indicated by the numeral 18 to the side of the filling neck and contains a dielectric block 19 on which is located a contact 20 to be engaged by the lateral arm 21 on the lower end of the switch arm 22 which works in the journal bracket 23 20 extending up along the exterior of the filling neck and having on its upper end the curved operating arm 24 which has attached to the back thereof the outwardly urging spring 25 which normally engages the exterior of the filling neck to keep 25 the operating member 24 in an outwardly swung position in which the contact arm 21 is disengaged from the contact 20. Pressing the operating arm 24 toward the filling neck will result in engaging the contact arm 21 with the contact 20 30 so as to close the circuit to the magnet 9, and energize the same, supposing the ignition switch to be in its "on" position and at the time the arm 24 is swung inwardly, the electro-magnet 9 will be energized so as to retract the plunger 10 in a 35 downward direction and out of locking relation to the filling neck cap 7. If the ignition switch (not shown) is not in its "on" position at the time of operating the switch arm 24, the electro-magnet 9 will not be energized.

The upper end of the filling neck has a radially inwardly extending flange 26 which has diametrically opposite openings 27 to receive, in the usual manner, the lugs 28 on the filling cap 7. The lugs 28 are shaped as indicated in Figure 5 and 45 angulated as indicated by the numeral 29. The cap has on its underside the usual compressible washer 30.

When the filling cap is placed in position on the filling neck by inserting the lugs 28 through 50 the openings 27 and the cap is turned in the locking direction, one of the lugs 28 will engage its inclined underside with the top of the plunger 10 and in further rotating in the locking direction, the cap will cause the plunger 10 to be de- 55

pressed against the tension of its spring 11, so that when the lug has passed the plunger 10 the plunger will spring up into place on the opposite side of the lug and act as a stop for positively preventing rotation of the cap in the unlocking direction, thereby locking the cap on the filling neck and preventing theft of the gasoline in the tank.

With the ignition switch of the automobile in the "on" position, the switch arm 24 may be pressed in the manner already indicated to retract the plunger 10 and enable rotating the filling neck cap in the unlocking direction.

Although I have shown and described herein a preferred embodiment of my invention, it is to be definitely understood that I do not desire to limit the application of the invention thereto, and any change or changes may be made in the materials, and in the structure and arrangement of the parts, within the spirit of the invention and the scope of the subjoined claims.

What is claimed is:—

1. In combination, a filling neck having a radially inward flange at its outer end formed with radially opposed openings therein, a filling neck cap having lugs adapted to be entered in said openings to assume a position under said flange when the cap is rotated in the locking direction, and a member arranged to assume a position relative to one of the lugs on the filling cap so as to

prevent movement of the lug in the unlocking direction, said member comprising a core, an electro-magnet in magnetic relation to said core, said core being normally spring-pressed in locking direction, and switch means mounted on the exterior of the filling neck for closing a circuit to the electro-magnet for retracting said member into the unlocking position.

2. In combination, a filling neck having a radially inward flange at its outer end formed with radially opposed openings therein, a filling neck cap having lugs adapted to be entered in said openings to assume a position under said flange when the cap is rotated in the locking direction, and a member arranged to assume a position relative to one of the lugs on the filling cap so as to prevent movement of the lug in the unlocking direction, said member comprising a core, an electro-magnet in magnetic relation to said core, said core being normally spring-pressed in locking direction, and switch means mounted on the exterior of the filling neck for closing a circuit to the electro-magnet for retracting said member into the unlocking position, said neck being provided with a shoulder, a housing mounted in the neck for electro-magnet and being disposed below the shoulder, a head on the member between the shoulder and the casing for limiting the movement of said member.

LEONARD RYDELL. 30
